CAR DUMPING APPARATUS

Ernest W. Taylor, Bay City, Mich., assignor to
Industrial Brownhoist Corporation, Bay City,
Mich., a corporation of Ohio

Application November 29, 1933, Serial No. 700,283

10 Claims. (Cl. 214—123)

This invention relates to improvements in car dumping apparatus and especially to an attachment for securing the car clamp assembly against vertical movement until the car has been shifted 5 and raised into proper relation with the clamp assembly proper.

In the well-known form of car dumping apparatus, a loaded car is run onto a cradle which is provided in a conventional tower so that the car 10 and cradle may be elevated and then tilted to discharge the car contents into a suitable chute or other receptacle. Usually a suitable car clamp or cover assembly is provided for regulating the flow of coal as it is discharged, said car 15 clamping means remaining stationary during the initial upward movement of the car and cradle, which movement brings the car into engagement and proper relation with the clamping means, after which the cradle, car, and clamping means 20 raise as a unit.

When mechanism of this type has been in use for a period of time, considerable fine material, such as coal or other granular particles, sifts into the vertical ways or guides in which the car 25 clamp assembly travels and freezes the mechanism. It has been found that in some instances there is no initial movement of the car and cradle, but that all parts raise as a unit; consequently, the cover of the car clamp assembly which limits 30 the discharging area of the car when it is in tilted position, is not properly spaced with relation to the top of the car; the discharging operation causes spillage and breakage, and is otherwise unsatisfactory, and where no cover is provided, 35 the car is not securely held and shifts on the cradle when turned to dumping position.

It is, therefore, the prime object of the invention to provide a latch mechanism associated with the car clamp assembly, and by means of 40 which said assembly is held stationary until the car and cradle have made the initial movement and the car engages and actuates said latch mechanism to release the clamping assembly, after which the car, cradle, and clamping mechanism raise as a unit and are tilted to dump the car, the clamping means or cover assembly being 45 properly positioned to control and confine the discharge of the coal.

Another object is to design simple, practical, 50 and economical latching means which is automatically actuated as the car is raised, and which positively releases the cover clamps so that they move with the car and cradle when the car is properly positioned with relation to said cover 55 clamps.

A further object is to provide simple and practical means for anchoring the cover clamps against vertical movement until the car has 5 raised to proper position and into contact with said latching mechanism, thereby insuring the cover being properly positioned with respect to the car, preventing any uncontrolled flow of coal or material when the car is tilted to dumping position, and eliminating the usual breakage occasioned thereby.

These and other features of the invention will be more fully apparent from the following specification, when read in connection with the accompanying drawings, in which:

Fig. 1 is an elevation illustrating coal handling 15 apparatus embodying the invention.

Fig. 2 is an enlarged fragmentary part sectional view showing the cradle, car, clamp, and cover member.

Fig. 3 is a fragmentary view similar to Fig. 2 20 and illustrating the car in raised position and the latch in its released position.

Fig. 4 is an enlarged detail of the car clamp and latch.

Fig. 5 is an enlarged fragmentary detail showing the mechanism in tilted position.

In the drawings the numeral 10 designates the usual tower or superstructure of the car dump. This is provided with the conventional trestle 11 between the ends of which a car cradle 12 is 30 located, so that the car "B" may be run onto the cradle for elevating and dumping its contents. Standard tracks or rails 13 are provided on the cradle 12, and suitable conventional shifting means 14 is provided so that the car may be 35 shifted against the side wall 15 of the cradle when the mechanism is actuated.

Guides 16 are formed in the side wall of the cradle, and vertically disposed posts 17 are slidably mounted therein, an overhanging head 18 being rigidly secured to each post, and each head is formed with ears 19 to which the clamps 20 are pivotally connected by means of the pins 21, a plate 22 being connected to these clamps and forming a cover for the open end of the car, all as described and claimed in my application for "Car dumping apparatus", filed May 8th, 1933, Serial No. 669,823, and while this application relates to a specific dumping apparatus, it will be 40 clearly understood that the mechanism herein described is not limited to any specific form, but is applicable to any dumping apparatus for insuring proper cooperation of the cover assembly 45 with the car when tilted to discharge the lead, 50 55 55

and also for securing proper positioning of the car on the cradle.

Counterweights 23 are connected to the cradle 12 by means of cables 24 and are trained over 5 the sheaves 25 and 26 which are mounted in the top of the tower, and in practice the cradle with the car thereon moves upwardly until the top of the car engages the heads 18 of the clamps 20 so that it is properly positioned with respect to 10 the cover or clamps; the mechanism then moves upward as a complete unit.

After the car dumper has been in use for a period of time, I have found that there is no initial movement of the car and cradle with respect to 15 the posts and clamps; consequently, the top of the car and the cover are not in proper relationship when the load is discharged, and this is due to the fine dust, slack, and similar material sifting into the guides 16 where it freezes and wedges 20 the posts so that they move with the cradle, and I have, therefore, provided means for positively anchoring the posts until this initial movement takes place and the car is elevated to proper position, 25 said means comprising latch mechanism which anchors the posts to supports 27 provided on the trestle, each support being formed with a jaw 28 as clearly shown in Fig. 4 of the drawings.

The latch mechanism includes a trip 29, one end being pivotally connected to the post at the point 30, the opposite end projecting outwardly beneath the head 18 and into the path of travel of the car as it is elevated. One end of a vertically disposed rod 31 is pivotally connected to the trip 29 at a point intermediate its length, the opposite end 35 being pivotally connected to the latch 32 by means of the pin 33, said latch being pivotally connected to the post at the point 34, the opposite leg of said latch being hook shaped as shown at 35, and when the mechanism is in position as shown in 40 Fig. 4 of the drawings, this hook engages the jaw 28 for firmly anchoring the post to the support, and when the car is raised, the upper edge engages the projecting trip 29, forcing it upwardly to position as shown in broken lines in Fig. 3 of the drawings, releasing the latch so that 45 the cradle, car, and posts move as a unit, until the cradle lugs 36 engage the brackets 37 provided on the tower so that the car and cradle are tilted and swung to position as clearly shown in Fig. 5 of the drawings, the clamps and cover 50 swinging over and forming a closure for the top of the car so that the discharge of the load is regulated.

A pan or apron 38 is connected to the tower at 55 the point 39, and onto which the material is discharged, said material flowing into a chute 40, and which is positioned over a ship, bin, or other receptacle (not shown), this apron and chute being adjustable in the conventional manner.

Suitable hoisting means (not shown) is provided for elevating the cradle and car, and after the load is discharged, the car and cradle are returned to original position, the latch 32 engaging and again anchoring the posts to the supports. 65 The empty car is then rolled away, and the next loaded car placed in position, and the cycle repeated.

The operation is simple, smooth, and positive, 70 it insures efficient dumping without spillage, it eliminates wedging and the breakage occasioned by the unrestrained flow of coal when the car is tilted without the cover being properly positioned, and insures the car being held against 75 shifting when tilted to discharge the load.

What I claim is:

1. In a car dumper, a tower, a cradle adapted to carry a car upwardly in the tower and at a certain elevation to tilt said car, posts mounted in said cradle and anchored in said tower, clamps secured to the upper end of said post, and means engageable by said car for releasing said posts when the car has been raised a predetermined distance to permit their upward travel as a unit with said cradle.

2. In a car dumper, a tower, a cradle adapted to carry a car upwardly in the tower and at a certain elevation to tilt said car, posts anchored in said tower and having clamps pivotally secured thereto, and latching means engageable by said car for releasing said posts and clamps to permit their upward travel as a unit with said cradle.

3. In a car dumper, a tower, a cradle adapted to carry a car upwardly in the tower and tilt said car, posts detachably anchored in the tower and 20 slidable in said cradle, cover clamps connected to the upper ends of said posts, and means engageable by said car for releasing said posts at a certain predetermined point in the upward travel of said car.

4. In a car dumping mechanism including a tower, a cradle mounted therein and adapted to carry a car upwardly and tilt said car to dump the contents thereof, spaced apart supports, posts anchored to said supports, and a latch mechanism projecting into the upward path of travel of the car for releasing said posts from said supports.

5. A car dumping mechanism including a tower, a cradle mounted in said tower and adapted to carry a car upwardly therein, a cover clamp assembly associated with the cradle and having a limited movement with relation thereto, spaced apart stationary supports, means anchored to said supports for securing the cover clamp assembly against vertical movement until the car is moved into engagement therewith, said means including a trip projecting into the path of travel of the car and adapted to be engaged thereby for releasing said cover clamp assembly from said supports at a predetermined point in the upward travel of the cradle.

6. An apparatus of the character described, a tower, a cradle mounted therein and adapted to carry a car upwardly in the tower and tilt said car to discharge the contents thereof, a counterbalanced cover assembly mounted in said tower and including posts slidably engageable with said cradle, means for anchoring said posts in said tower, and latching means engageable by said car for releasing said posts at a predetermined point in the upward travel of said car.

7. An apparatus of the character described comprising a tower, a cradle mounted in the tower and adapted to carry a car upwardly and tilt to discharge the contents thereof, a counterbalanced cover assembly, spaced apart supports, posts anchored to said supports and having their upper ends pivotally connected to said cover assembly, and means for releasing said posts from said supports at a predetermined point in the upward travel of said cradle.

8. An apparatus of the character described comprising a tower, a cradle mounted in the tower and adapted to carry a car upwardly and at a certain elevation to tilt to discharge the contents thereof, a counterweighted cover assembly mounted on said cradle and having a limited sliding movement with relation thereto, means for anchoring said cover to said tower, and means ex-

tending into the path of travel of the car for releasing said cover assembly at a predetermined point of travel of said car.

9. In a car dumping apparatus comprising a tower, a car cradle mounted in the tower and adapted to carry the car upwardly and at a certain point to be tilted to cause the contents of the car to be dumped therefrom, a cover assembly mounted on the cradle and having a limited vertical movement with relation thereto, spaced apart supports and to which said cover assembly is detachably anchored, and means on the cradle for releasing said cover assembly at a certain

predetermined point in the upward travel of said cradle.

10. In a car dumping apparatus comprising a tower, a cradle mounted in said tower and adapted to carry a car upwardly therein, a cover assembly associated with the cradle and including spaced apart posts mounted to slide therein, spaced apart supports, a latch for detachably securing said posts to said supports, and a trip member projecting into the path of travel of the car and adapted to be actuated thereby to release said posts from said supports. 5 10

ERNEST W. TAYLOR.
